CLAIM

The ornamental design for a vial access device, as shown and described.

DESCRIPTION

FIG. 1 is a perspective view of a vial access device showing our new design;

FIG. 2 is another perspective view thereof;

FIG. 3 is a top plan view thereof;

FIG. 4 is a bottom plan view thereof;

FIG. 5 is a front elevational view thereof;

FIG. 6 is a back elevational view thereof; and,

FIG. 7 is a side elevational view thereof, the opposite side elevational view being a mirror image thereof.
